United States Patent Office

Des. 197,751
Patented Mar. 17, 1964

197,751

VAGINAL APPLICATOR

William R. Rigney, Watchung, and Bernard F. Major,
Somerville, N.J., assignors to Ortho Pharmaceutical Corporation, a corporation of New Jersey

Filed July 24, 1963, Ser. No. 75,949

Term of patent 14 years

(Cl. D83—12)

We claim:
The ornamental design for a vaginal applicator, as shown.
